AIR CONDITIONING CONTROL SYSTEM

Leo B. Miller, Hartsdale, N. Y., and William L. McGrath, St. Paul, Minn., assignors to Minneapolis-Honeywell Regulator Company, Minneapolis, Minn., a corporation of Delaware

Application June 11, 1937, Serial No. 147,694

9 Claims. (Cl. 62—6)

This invention relates to control systems in general and more particularly to control systems for air conditioning apparatus.

In the past, control systems for air conditioning apparatus have had their control instrumentalities located at various positions, such as adjacent to the conditions to which they respond, and consequently they have been widely spaced from each other and from the apparatus which they control. As a result long runs of wiring were required which necessarily increased the installation costs. Further, the installation men were not always familiar with the control systems they were installing and it was not unlikely for them to connect up these widely spaced control instrumentalities incorrectly even though specific instructions were issued to them. This invariably caused unsatisfactory operation of the air conditioning system. As is often the case, the control instrumentalities must be adjusted with respect to each other to make the control system operate properly and a great deal of time was expended by the installer or service men in moving from one control instrumentality to another. These difficulties, as well as many others, not only caused the installation and servicing costs to remain high but also increased the possibility of errors upon the part of the service or installation men.

In application Serial No. 146,756, filed by Clarence W. Nessell on June 7, 1937, one arrangement for overcoming the above difficulties is disclosed.

It is an object of this invention to provide an improved arrangement for obviating the above difficulties whereby installation and servicing costs are reduced to a minimum and whereby the chances of error on the part of the installation or service men is also reduced to a minimum much to the benefits of the air conditioning trade and the ultimate user.

The unitary control arrangement of the above referred to Clarence W. Nessell application is composed of a group of standard instruments mounted in a common housing. Although such an arrangement reduces installing errors and installation and servicing costs, it is relatively expensive to manufacture inasmuch as it is composed of standard instruments. As will be apparent these standard instruments must be self contained, extremely rugged in nature and enclosed in individual casings for universal use in the field with the result that they are comparatively expensive to manufacture.

It is therefore a further object of this invention 55 to provide a new and novel unitary control arrangement embodying the above principles.

Another object of this invention is to provide a novel control arrangement for an air conditioning apparatus to obtain in a new and improved manner a desired sequence of control.

Other objects and advantages will become apparent to those skilled in the art upon reference to the accompanying specification, in claims and drawings.

For a more thorough understanding of this invention, reference is made to the accompanying drawings in which

Figure 1 is a sectional view taken substantially along the line 1—1 of Figure 2 showing one

to reduce costs of the manufacture of the unitary control arrangement which, when taken in connection with reductions in installation and service costs, provides an extremely desirable advance in the art of automatic control systems. In carrying out this object of the invention control elements or units as distinguished from standard instruments are utilized. These control elements are reduced to simple movements and by reason of their novel construction all of the hitherto known complex adjusting means are eliminated. In addition these simple control elements are constructed to be mounted on control panels, in many instances in conjunction with other control elements, and therefore they need not be self contained, enclosed in individual casings or rugged in construction, all of which leads to reduced production costs.

These simple control elements may be fabricated so as to be responsive to any desired conditions, such as, pressure, temperature, humidity, etc., and if it be desired to control an apparatus in accordance with any condition or combination of conditions, the proper control element or elements may be selected, mounted on a common panel and connected together to perform the desired control sequence. A large number of these simple control elements can be manufactured and stocked and then selected according to the control sequence desired and by reason of this mass production, production costs are further decreased. A unitary control arrangement relatively inexpensive in cost may therefore be readily fabricated to meet practically any control problem and such unitary control arrangement, containing all of the control instrumentalities, may be readily and cheaply mounted on the apparatus which it controls.

Therefore, a further object of this invention is to provide a new and novel unitary control arrangement embodying the above principles.

Another object of this invention is to provide a novel control arrangement for an air conditioning apparatus to obtain in a new and improved manner a desired sequence of control.

Other objects and advantages will become apparent to those skilled in the art upon reference to the accompanying specification, in claims and drawings.

For a more thorough understanding of this invention, reference is made to the accompanying drawings in which

Figure 7 is a partial sectional view taken substantially along the line 7—7 of Figure 4 to more clearly illustrate the adjusting mechanism utilized in Figure 4.

Referring now to Figures 1 and 2 an air conditioning apparatus is generally designated at 10 for conditioning the air of a space. The air conditioning apparatus 10 is provided with a return air opening 11 which leads to a return air chamber 12. Located in the return air chamber 12 are fans 13 operated by an electric motor 14 for forcing return air over a cooling coil 15 into a delivery chamber 16. Cooled air is conducted from the delivery chamber 16 through an opening 17 to the space to be conditioned. The cooling coil 15 is illustrated as being of the direct expansion type. Located below the return air chamber 12 is a chamber 18 which encloses a mechanical refrigerating apparatus. The mechanical refrigerating apparatus is shown to include a condenser 19 and a compressor 20. Compressed refrigerant is discharged by the compressor 20 through a high pressure pipe 21 into the condenser 19 where it is liquefied. Condensed refrigerant passes through a liquid line 22 and an expansion valve 23 into the direct expansion coil 15. Expanded refrigerant is withdrawn from the direct expansion coil 15 through a suction pipe 24 by the compressor 20. Since this mechanical refrigerating apparatus is conventional a further description thereof is not considered necessary.

Also located in the chamber 18 is a partition 26 upon which is mounted the unitary control arrangement generally designated at 27. Referring now to Figure 3 the unitary control arrangement 27 is shown to comprise a common mounting structure or panel 28 upon which are mounted the various basic control elements or units. A control unit responsive to changes in space temperature is generally designated at 29, a control unit responsive to variations in suction pressure of the refrigerating apparatus is generally designated at 30 and a control unit responsive to changes in high pressure of the refrigerating apparatus is generally designated at 31. These three control units are adapted to control a relay or starter generally designated at 32 and if desirable, this relay or starter 32 may include overload switching mechanism to provide overload protection. Power is supplied to the relay 32 by means of a step down transformer generally designated at 33. A combined manual and overload cut-out switching mechanism for controlling the operation of the fan 14 is generally designated at 34 and a switch for placing the control system in operation is generally designated at 35. Suitable terminal blocks for connecting the unitary control arrangement to the fan motor 14, a source of power, and the com-

pressor motor 20 are generally designated at 36, 37, and 38, respectively.

Referring now to Figures 3 and 4 the space temperature responsive control unit is shown to comprise a substantially flat plate 40 on one side of which is secured a bellows assembly 41 as by screws 42. The bellows assembly 41 is connected by a capillary tube 43 to a bulb 44 located in the return air chamber 12. The bulb 44 is preferably charged with a volatile fluid so that the bellows assembly 41 is operated in accordance with changes in space temperature. The bellows assembly 41 operates a plunger 45 which engages a lever 46 pivoted at 47 to a bracket 48 carried by the flat plate 40. A spring 49 maintains the lever 46 in engagement with the plunger 45. Resilient switch arms 51 and 52 are carried by the lever 46 and these switch arms are braced by means of brackets 53. The brackets 53 and the switch arms 51 and 52 are connected to the lever 46 and to conductors 55 by screws 54. The conductors 55 are in turn connected by suitable lead wires 56 to terminals 57 mounted on an insulated block 58 secured to the plate 40 by screw 59. The switch arms 51 and 52 are adapted to engage an adjustable contact 60 and a stationary contact 61 carried by brackets 62 and 63 respectively. The brackets 62 and 63 are also secured to the terminal block 58 as by rivets 64. The brackets 62 and 63 extend through the terminal block 58 and an opening 65 in the plate 40 and an opening 66 in the plate 28 allow the terminals to extend therethrough as well as the bellows assembly 41. By reason of this arrangement the wiring connections may be made at the rear of the panel while only the switching mechanism is located on the front of the panel.

A U-shaped bracket extends forwardly from the plate 40 and is provided with a bearing 69 for a rotatable shaft 70. The shaft 70 is rigidly secured to a cup 71 which in turn is rigidly secured to a nut 72. The nut 72 engages a screw member 73 which is provided with four projections 74 as illustrated in Figure 7. A plate 75 is provided with suitable apertures which are engaged by the projections 74 and the plate 75 is provided with ears 76 which are adapted to slide in slots 77 located in the U-shaped member 68. The plate 75 is prevented from rotating by the ears 76 and therefore the screw member 73 is also prevented from rotating. Since the screw member 73 cannot rotate, rotation of the shaft 70 and the nut 72 therefore causes longitudinal movement of the screw member 73. A screw 78 threaded into the screw member 73 adjusts the plate 5 with respect to the screw member 73 and therefore provides means for obtaining factory calibration of the control unit. A spring 79 engages the plate 75 and also engages an abutment member 80 which in turn engages the lever 46. A handle 82 is secured to the shaft 70 for causing longitudinal movement of the plate 75 and therefore adjustment of the compression in the spring 79. The spring 79 urges the switch arms 51 and 52 away from the contacts 62 and 63, respectively. Upon an increase in space temperature the bellows assembly acts against the spring 79 to move the switch arms 51 and 52 into engagement with the contacts 60 and 61, respectively. By adjusting the compression in the spring 79 the temperature value at which the switch arm 52 engages the contact 61 may be varied and also by adjusting the adjustable contact 60 the temperature at which the

switch arm 51 engages the contact 60 may be varied. Preferably, the switch arm 51 engages the adjustable contact 60 before the switch arm 52 engages the stationary contact 61. For purposes of illustration it is assumed that the switch arm 51 engages the adjustable contact 60 when the temperature increases to 73° and the switch arm 52 engages the stationary contact when the temperature increases to 75°.

Referring now to Figures 3 and 6 the suction pressure control unit 30 is shown to comprise a substantially flat plate 85 to which is suitably secured a bellows assembly 86. The bellows assembly 86 is shown to comprise a bellows 87 sealed at one end to the casing and at the other end to a movable plate 88. The movable plate 88 carries a plunger 89 in which is screw threadedly mounted an abutment 90 for engaging a lever 91. The lever 91 is pivoted at 92 to a bracket 112 carried by the plate 85 and a spring 93 urges the lever 91 into engagement with the abutment 90. A spring 94 is located between the movable plate 88 and an adjusting nut 95. By suitably rotating the nut 95 the compression in the spring 94 may be varied. The bellows assembly 86 is connected by a pipe 96 to the suction pressure pipe 24 of the mechanical refrigerating apparatus. The lever 91 carries resilient switch arms 97 and 98 which are braced by brackets 99. The switch arms 97 and 98 and the brackets 99 are secured to the lever 91 and to conductors 101 by screws 100. The conductors 101 are electrically connected by lead wires to terminals 103 carried by an insulating block 104 which in turn is secured to the plate 85 by screws 105. The switch arms 97 and 98 are adapted to engage contacts 106 and 107, respectively. The contacts 106 and 107 are carried by brackets 108 which extend through the terminal block 104 and are secured thereto by means of rivets. Preferably, the contact 106 is made adjustable. The plate 85 and the panel 28 are provided with apertures 110 and 111 to accommodate the terminals of the terminal block 104 whereby all of the wiring connections may be made at the rear of the panel 28. The aperture 111 also accommodates the bellows assembly 86. Upon an increase in suction pressure the movable plate 88 is operated against the action of the spring 94 to move the switch arm 97 into engagement with the adjustable contact 106 and to move the switch arm 98 into engagement with the stationary contact 107. Preferably, the switch arm 97 engages the contact 106 before the switch arm 98 engages the contact 107. For purposes of illustration it is assumed that the switch arm 97 engages the contact 106 when the pressure increases to 20 pounds and the switch arm 98 engages the contact 107 when the pressure increases to 50 pounds.

In Figure 5 the high pressure responsive control unit 31 is shown to comprise a substantially flat plate 115 suitably secured to the panel 28. A bellows assembly 116 is secured to the plate 115 and is provided with a pipe 117 leading to the high pressure pipe 21. The bellows assembly 116 operates a plunger 118 in which is screw threadedly mounted an abutment 119 for engaging a lever 120 pivoted at 121 to a bracket 122 carried by the plate 115. A spring 123 maintains the lever 120 in engagement with the abutment 119. A nut 124 adjusts a spring located in the bellows assembly for adjusting the pressure setting of the control unit. The lever 120 carries resilient switch arms 125 and 126 which are

braced by brackets 127. The switch arms 125 and 126 and the brackets 127 are secured to the lever 120 and to conductors 129 by screws 128. The conductors 129 are connected by lead wires 5 to terminals 131 carried by a terminal block 132 mounted on the plate 115 by screws 133. The switch arms 125 and 126 are adapted to engage contacts 134 and 135, respectively. The contacts 134 and 135 are carried by brackets 136 and 137, 10 respectively, which extend through the terminal block 132 and which are connected thereto by means of rivets. The plate 115 and the panel 28 are provided with apertures 138 and 139, respectively, for accommodating the terminals carried by the terminal block 132 whereby the wiring connections may be made at the rear of the panel 28. The aperture 139 in the panel 28 also accommodates the bellows assembly 116. Preferably, the adjusting nut 124 and the adjustable contact 134 are so adjusted that the switch arm 126 is moved out of engagement with the contact 135 when the high pressure increases to 135 pounds and the switch arm 125 moves out of engagement with the contact 134 when the high pressure increases to 185 pounds.

From the above it is seen that each of the condition responsive control units includes a plate which is particularly adapted to be mounted on a common control panel, a relatively simple switching mechanism carried by the plate, a relatively simple condition responsive device carried by the plate and terminals electrically connected with the switching mechanism also carried by the plate. This provides an extremely simple basic control unit which may be manufactured in relatively large quantities and readily mounted on a control panel. By manufacturing these different types of control units in large quantities they can be produced very cheaply. Now if 30 it be desired to form a unitary control arrangement, all that is necessary is to select the types of control units desired, mount these control units on a common panel and electrically interconnect the control units in a manner which will 35 provide the desired control sequence. Such a method of formulating a unitary control arrangement greatly reduces the cost of manufacture.

The starter or relay for controlling the operation of the compressor motor 20 may comprise a plate 143 suitably mounted to the control panel 28. The various parts of the relay are mounted on the plate 143 so that a relay unit may be prefabricated and then secured to the control 40 panel 28. The relay unit may comprise a relay coil 144 for operating an armature 145 which carries switch arms 146, 147, 148, and 149. Upon energization of the relay coil 144 the switch arms 146, 147, 148, and 149 are moved into engagement with stationary contacts 150, 151, 152, and 153, respectively. If desired the relay or starter unit may include overload cut-out switches generally designated at 154 and 155. These switches may include a thermostatic element 156 anchored at one end by a bracket 157 and operating contacts 158. The bimetallic elements 156 45 may be heated by heaters 159, the arrangement being such that when the current flowing through the heaters reaches a predetermined high value, the bimetallic elements 156 are flexed to open the contacts 158. Suitable latching mechanism may be provided for maintaining the contacts 158 separated upon the occurrence of 50 overload conditions whereupon manual resetting 70 would be necessary. Since such a construction 75

is old in the art the overload cut-out switch mechanism 154 and 155 have only been diagrammatically shown.

The step-down transformer 33 carried by the panel 28 is shown to comprise a primary 161 and a secondary 162. The combined manual and overload cut-out switching mechanism 34 carried by the panel 28 is shown to comprise a bimetallic element 165 suitably secured to a bracket 166 for operating contacts 167. The bimetallic element 165 is heated by a heater 168, the arrangement being such that when an overload condition occurs, the heater 168 flexes the bimetallic element 165 to open the contacts 167. Suitable latching mechanism may be provided for required resetting of the switching mechanism upon the occurrence of overload conditions. An operating handle 169 is also provided for manually operating the contacts 167. The switch 35 which places the control system for the relay or starter 32 into or out of operation is shown to comprise a manually operated switch arm 172 and a stationary contact 173. The terminal block 36 includes terminals 175 and 176, the terminal block 37 includes terminals 177, 178, and 179, and the terminal block 38 includes terminals 180, 181, and 182.

The terminals 177, 178, and 179 of the terminal block 37 are shown to be connected to a three-phase source of power. The terminals 180, 181, and 182 are suitably connected to the compressor motor 20 and the terminals 175 and 176 are suitably connected to the fan motor 14. Whenever the relay coil 144 of the starter 32 is energized to move the switch arms 146, 147, 148, and 149 into engagement with the contacts 150, 151, 152, and 153, respectively, the compressor motor 20 is connected to the source of power. The heaters 159 of the overload cut-out switching mechanisms 154 and 155 are included in two of the phase connections leading from the source of power to the compressor motor 20 so that if an overload condition exists in any of the phase circuits the contacts 158 of the overload cut-out switching mechanisms 154 and 155 are open. The primary 161 of the step-down transformer 33 is connected across the terminals 177 and 178 so that power is at all times supplied to the step-down transformer 33.

Closure of the contacts 167 of the combined overload and manual switch 34 completes a circuit from the secondary 162 through the heater 168, contacts 167, terminal 175, fan motor 14, and terminal 176 back to the secondary 162. Completion of this circuit causes operation of the fans 13 to deliver conditioned air to the space to be conditioned. If an overload condition exists within the fan circuit the contacts 167 are separated to shut down the fan 14 whereby overload protection is provided. When the switch arm 172 of the switch 35 engages the contact 173 power is supplied to the operating coil 144 of the relay 32 and this supply of power passes through the heater 168 and contacts 167 of the combined manual and overload cut-out switch 34. Therefore if the contacts 167 are separated, the supply of power to the relay or starter 32 is interrupted even though the switch 35 is closed. Therefore it is impossible to operate the relay 32 in case the fan motor 14 is not operating.

Assume now that the space temperature rises to 75° to move the switch arms 51 and 52 into engagement with the contacts 60 and 61, that the suction pressure increases to 50 pounds to move the switch arms 97 and 98 into engage-

ment with the contacts 106 and 107 and that the high pressure is below 135 pounds so that the switch arms 125 and 126 are engaging the contacts 134 and 135, a circuit is completed from the secondary 162 through heater 168, contacts 167, switch arm 172, contact 173, contact 134, switch arm 125, contact 60, switch arm 51, contact 106, switch arm 97, switch arm 98, contact 107, switch arm 52, contact 61, switch arm 126, contact 135, relay coil 144, contacts 158 and bimetallic element 156 of the overload cut-out switch 155 and contacts 158 and bimetallic element 156 of the overload cut-out 154 back to the secondary 162. Completion of this circuit causes energization of the relay coil 144 to pull in the starter or relay 32 to cause operation of the mechanical refrigerating apparatus. When the starter or relay 32 is thus pulled in, switch arm 146 engages contact 150 to complete a maintaining circuit for the relay coil 144 which shunts out switch arm 88 and contact 107 of the suction pressure controller, switch arm 52 and contact 61 of the temperature controller 28 and switch arm 126 and contact 135 of the high pressure controller 31. This maintaining circuit may be traced from the secondary 162 through heater 168, contacts 167, switch arm 172, contact 173, contact 134, switch arm 125, contact 60, switch arm 51, contact 106, switch arm 97, switch arm 146, contact 150, relay coil 144, contacts 158, and bimetallic element 156 of the overload cut-out 155, and contacts 158 and bimetallic element 156 of the overload cut-out 154 back to the secondary 162. Completion of this circuit maintains the relay or starter 32 energized even though the space temperature should drop below 75°, or the suction pressure should drop below 50 pounds, or the high pressure should increase above 135 pounds. This maintaining circuit will therefore maintain the refrigerating apparatus in operation until the space temperature shall decrease to the desired value of 73° whereupon the switch arm 51 is moved out of engagement with the contact 60, or until the suction pressure shall decrease to 20 pounds whereupon the switch arm 97 moves out of engagement with the contact 106, or until the high pressure increases to 185 pounds whereupon the switch arm 125 moves out of engagement with the contact 134. Whenever any of these last contingencies occur the relay coil 144 is deenergized to drop out the relay or starter 32 and stop operation of the compressor 20. In order to restart the refrigerating apparatus the space temperature must again rise to 75°, the suction pressure must raise to 50 pounds and the high pressure must decrease to 135 pounds. By reason of the above control arrangement the refrigerating apparatus is operated to maintain the space temperature substantially between 73 and 75° and this operation is protected against current overload conditions in the refrigerating apparatus, high pressure conditions on the high pressure side of the refrigerating apparatus, and low pressure conditions on the low pressure side of the refrigerating apparatus. Also if the fan motor 14 should be stopped either by manually opening the switch 34 or should be stopped upon the occurrence of overload conditions the refrigerating apparatus is shut down since there is no need for operating the refrigerating apparatus if the fan motor 14 is not operating. It is here noted that in order to restart the refrigerating apparatus the suction pressure must raise to some predetermined value, 50 pounds as illustrated,

whereby the starting effort of the compressor motor is reduced.

From the above it is seen that this invention not only includes a novel method of fabricating a control system utilizing a unitary control arrangement but also applies in a new manner this novel control system to an air conditioning apparatus for controlling the same in a new and novel manner. Although for purposes of illustration we have disclosed one form of our invention, other forms thereof may become apparent to those skilled in the art upon reference to this specification and therefore this invention is to be limited only by the scope of the appended claims and prior art.

We claim as our invention:

1. In a control system for a mechanical refrigerating apparatus, the combination of, a first control unit including a device responsive to changes in a condition produced by the refrigerating apparatus and a pair of switches sequentially opened and closed thereby, a second control unit including a device responsive to changes in suction pressure of the refrigerating apparatus and a pair of switches sequentially opened and closed thereby, a third control unit including a device responsive to changes in high pressure of the refrigerating apparatus and a pair of switches sequentially opened and closed thereby, a starter for controlling the operation of the refrigerating apparatus, and connections between all of the switches and the starter for starting the refrigerating apparatus when all of the switches are closed and for continuing operation of the refrigerating apparatus as long as one of the switches of each pair is closed.

2. In a control system for a mechanical refrigerating apparatus, the combination of, a first control unit including a device responsive to changes in a condition produced by the refrigerating apparatus and a pair of switches sequentially opened and closed thereby, a second control unit including a device responsive to changes in suction pressure of the refrigerating apparatus and a pair of switches sequentially opened and closed thereby, a third control unit including a device responsive to changes in high pressure of the refrigerating apparatus and a pair of switches sequentially opened and closed thereby, a starter for controlling the operation of the refrigerating apparatus, and connections between all of the switches and the starter for starting the refrigerating apparatus when all of the switches are closed and for continuing operation of the refrigerating apparatus as long as one of the switches of each pair is closed, and means for mounting the starter and all of the control units on a common mounting structure to provide a unitary control arrangement for the refrigerating apparatus.

3. In a control system for a refrigerating apparatus having an evaporator for controlling the condition of a medium and an electrically operated mechanism for controlling the circulation of refrigerant through the evaporator, the combination of, first and second switch means, control means responsive to the condition of the medium being controlled by the evaporator for closing the first switch means when the condition rises to a predetermined high value and for opening the second switch means when the condition decreases to a predetermined low value, third and fourth switch means, control means responsive to a condition which is a measure of evaporator temperature for closing the third switch means when the

evaporator temperature rises to a predetermined high value and for opening the fourth switch means when the evaporator temperature decreases to a predetermined low value, means for completing a starting circuit through the first and third switch means to operate the electrically controlled mechanism to start circulation of refrigerant through the evaporator, a maintaining switch, means for closing the maintaining switch as an incident to completion of the starting circuit, and means for completing a maintaining circuit through the second and fourth switch means and the maintaining switch to maintain the electrically controlled mechanism in operation and circulation of refrigerant through the evaporator, said maintaining switch remaining closed as long as the maintaining circuit is completed.

4. In a control system for a refrigerating apparatus having an evaporator for controlling the condition of a medium and an electrically operated mechanism for controlling the circulation of refrigerant through the evaporator, the combination of, first and second switch means, control means responsive to the condition of the medium being controlled by the evaporator for closing the first switch means when the condition rises to a predetermined high value and for opening the second switch means when the condition decreases to a predetermined low value, third and fourth switch means, control means responsive to a condition which is a measure of evaporator temperature for closing the third switch means when the evaporator temperature rises to a predetermined high value and for opening the fourth switch means when the evaporator temperature decreases to a predetermined low value, fifth and sixth switch means, control means responsive to the pressure on the high pressure side of the refrigerating apparatus for closing the fifth switch means when the pressure decreases to a predetermined low value and for opening the sixth switch means when the pressure increases to a predetermined high value, means for completing a starting circuit through the first, third and fifth switch means to operate the electrically controlled mechanism to start circulation of refrigerant through the evaporator, a maintaining switch, means for closing the maintaining switch as an incident to completion of the starting circuit, and means for completing a maintaining circuit through the second, fourth and sixth switch means and the maintaining switch to maintain the electrically operated control mechanism in operation and circulation of refrigerant through the evaporator, said maintaining switch remaining closed as long as the maintaining circuit is completed.

5. In a control system for a refrigerating apparatus having an evaporator for controlling the condition of a medium and an electrically operated mechanism for controlling the circulation of refrigerant through the evaporator, the combination of, first and second switch means, control means responsive to the condition of the medium being controlled by the evaporator for closing the first switch means when the condition rises to a predetermined high value and for opening the second switch means when the condition decreases to a predetermined low value, third and fourth switch means, control means responsive to a condition which is a measure of evaporator temperature for closing the third switch means when the evaporator temperature rises to a predetermined high value and for opening the fourth switch means when the condition decreases to a predetermined low value, fifth and sixth switch means, control means responsive to the pressure on the high pressure side of the refrigerating apparatus for closing the fifth switch means when the pressure decreases to a predetermined low value and for opening the sixth switch means when the pressure increases to a predetermined high value, means for completing a starting circuit through the first, third and fifth switch means to operate the electrically controlled mechanism to start circulation of refrigerant through the evaporator, a maintaining switch, means for closing the maintaining switch as an incident to completion of the starting circuit, and means for completing a maintaining circuit through the second, fourth and sixth switch means and the maintaining switch to maintain the electrically operated control mechanism in operation and circulation of refrigerant through the evaporator, said maintaining switch remaining closed as long as the maintaining circuit is completed.

determined high value and for opening the fourth switch means when the evaporator temperature decreases to a predetermined low value, means for completing a starting circuit through the first and third switch means to operate the electrically controlled mechanism to start circulation of refrigerant through the evaporator, a maintaining switch, means for closing the maintaining switch as an incident to completion of the starting circuit, means for completing a maintaining circuit through the second and fourth switch means and the maintaining switch to maintain the electrically controlled mechanism in operation and circulation of refrigerant through the evaporator, said maintaining switch remaining closed as long as the maintaining circuit is completed, and means for mounting all of the switch means and the control means on a common mounting structure to provide a unitary control arrangement for the refrigerating apparatus.

6. In a control system for a refrigerating apparatus having an evaporator for controlling the condition of a medium and an electrically operated mechanism for controlling the circulation of refrigerant through the evaporator, the combination of, first and second switch means, control means responsive to the condition of the medium being controlled by the evaporator for closing the first switch means when the condition rises to a predetermined high value and for opening the second switch means when the condition decreases to a predetermined low value, third and fourth switch means, control means responsive to a condition which is a measure of evaporator temperature for closing the third switch means when the evaporator temperature rises to a predetermined high value and for opening the fourth switch means when the evaporator temperature decreases to a predetermined low value, fifth and sixth switch means, control means responsive to the pressure on the high pressure side of the refrigerating apparatus for closing the fifth switch means when the pressure decreases to a predetermined low value and for opening the sixth switch means when the pressure increases to a predetermined high value, means for completing a starting circuit through the first, third and fifth switch means to operate the electrically controlled mechanism to start circulation of refrigerant through the evaporator, a maintaining switch, means for closing the maintaining switch as an incident to completion of the starting circuit, means for completing a maintaining circuit through the second, fourth and sixth switch means and the maintaining switch to maintain the electrically operated control mechanism in operation and circulation of refrigerant through the evaporator, said maintaining switch remaining closed as long as the maintaining circuit is completed, and means for mounting all of the switch means and the control means on a common mounting structure to provide a unitary control arrangement for the refrigerating apparatus.

7. In a control arrangement for an air conditioning apparatus including a refrigerating apparatus having an evaporator for cooling air and a mechanism for controlling the circulation of refrigerant through the evaporator and air circulating means for circulating air over the evaporator, the combination of, controls means responsive to the temperature of the air, control means responsive to a condition which is a measure of evaporator temperature, controlling means

controlled by both control means for controlling the operation of the mechanism to start circulation of refrigerant through the evaporator only when the temperature of the air rises to a predetermined high value and the evaporator temperature rises to a predetermined high value and to stop circulation of refrigerant through the evaporator when either the temperature of the air decreases to a predetermined low value or the evaporator temperature decreases to a predetermined low value, and control means for controlling the operation of the air circulating means, said last mentioned control means also controlling the controlling means to stop circulation of refrigerant through the evaporator when the air circulating means is stopped and to start circulation of refrigerant through the evaporator upon starting of the air circulating means only when the temperature of the air rises to the predetermined high value and the evaporator temperature rises to the predetermined high value.

8. In a control arrangement for an air conditioning apparatus including a refrigerating apparatus having an evaporator for cooling air and a mechanism for controlling the circulation of refrigerant through the evaporator and air circulating means for circulating air over the evaporator, the combination of, control means responsive to the temperature of the air, control means responsive to the pressure on the high pressure side of the refrigerating apparatus, control means responsive to a condition which is a measure of evaporator temperature, controlling means controlled by all of the control means for controlling the operation of the mechanism to start circulation of refrigerant through the evaporator only when the temperature of the air rises to a predetermined high value, the pressure on the high pressure side decreases to a predetermined low value and the evaporator temperature increases to a predetermined high value and to stop circulation of refrigerant through the evaporator when either the temperature of the air decreases to a predetermined low value, the pressure on the high pressure side increases to a predetermined high value or the evaporator temperature decreases to a predetermined low value, and control means for controlling the operation of the air circulating means, said last mentioned control means also controlling the control means to stop circulation of refrigerant through the evaporator when the air circulating means is stopped and to start circulation of refrigerant through the evaporator upon starting of the air circulating means only when the temperature of the air rises to the predetermined high value, the pressure on the high pressure side decreases to the predetermined low value and the evaporator temperature rises to the predetermined high value.

9. In a control arrangement for an air conditioning apparatus including a refrigerating apparatus having an evaporator for cooling air and a compressor for circulating refrigerant through the evaporator and air circulating means for circulating air over the evaporator, the combination of, control means responsive to the temperature of the air, control means responsive to the pressure on the high pressure side of the refrigerating apparatus, control means responsive to a condition which is a measure of evaporator temperature, controlling means controlled by all of the control means for controlling the operation of the compressor to start circulation of

refrigerant through the evaporator only when the temperature of the air rises to a predetermined high value, the pressure on the high pressure side decreases to a predetermined low value and the evaporator temperature increases to a predetermined high value and to stop circulation of refrigerant through the evaporator when either the temperature of the air decreases to a predetermined low value, the pressure on the high pressure side increases to a predetermined 10

high value or the evaporator temperature decreases to a predetermined low value, and control means for controlling the operation of the air circulating means, said last mentioned control means also controlling the controlling means to stop circulation of refrigerant through the evaporator when the air circulating means is stopped.
